DESIGN FOR A RIM BUTTON

Charles H. Frank, New Rochelle, N. Y.

Application June 19, 1946, Serial No. 130,863

Term of patent 7 years

(Cl. D17—2)

To all whom it may concern:

Be it known that I, Charles H. Frank, a citizen of the United States, residing in New Rochelle, county of Westchester, State of New York, have invented a new, original, and ornamental Design for a Rim Button, of which the following is a specification, reference being had to the accompanying drawing, forming a part thereof, in which:

Fig. 1 is a top plan view of my new design of a rim button;

Fig. 2 is a bottom plan view thereof;
Fig. 3 is a side elevational view thereof, and
Fig. 4 is a cross-sectional view taken on line
4—4 of Fig. 1.

I claim:

The ornamental design for a rim button, as shown.

CHARLES H. FRANK.
